UNITED STATES PATENT OFFICE.

HORACE M. SMITH, OF CHICAGO, ILLINOIS, ASSIGNOR TO LIQUID CARBONIC COMPANY, OF CHICAGO, ILLINOIS, A CORPORATION OF ILLINOIS.

CARBONATOR FOR BEVERAGES AND THE LIKE.

1,258,369.

Specification of Letters Patent.

Patented Mar. 5, 1918.

Application filed September 20, 1915. Serial No. 51,599.

To all whom it may concern:

Be it known that I, HORACE M. SMITH, a citizen of the United States, residing at Chicago, county of Cook, and State of Illinois, have invented certain new and useful Improvements in Carbonators for Beverages and the like, of which the following is a specification.

My invention relates more particularly to that class of carbonators which comprise a reservoir, the contents of which are intermittently and irregularly tapped or withdrawn for consumption or use, such for example as are used in connection with bottling machines and soda fountains. In such constructions a saturating chamber ordinarily surmounts the reservoir and is arranged to be connected by suitable pipes with pressure tubes containing carbonic acid gas under high pressure and with a source of water supply. In order to force the water into the saturating chamber against the pressure of the gas therein it is necessary to employ a pump which is usually driven from some suitable source of power and controlled as to its periods of operation by the level of the liquid in the reservoir, being set in operation whenever the liquid falls below a predetermined level. The preferred form of saturating chamber is vertically elongated and, as ordinary water contains considerable air which is more or less released or substituted by the carbonic acid gas taken up by the water in the saturating chamber, the air tends to collect in the upper end of said chamber, thereby reducing the efficiency of the latter. It is ordinary practice to provide a valve for snifting or exhausting the air in the upper end of the saturating chamber which is opened whenever it occurs to the attendant that the device needs snifting. As the carbonator is ordinarily in a cellar or some other out of the way place, the snifting operation is very apt to be neglected, thus impairing the efficiency of the operation of the carbonator. It is the object of my invention to provide for automatically snifting the saturating chamber at suitable intervals and to a desired extent. For this purpose I provide a snifting valve and a motor for operating the same which is controlled indirectly by the same mechanism which controls the operation of the pump so that every time the pump is operated to

increase the charge of water in the reservoir or its operation ceases the saturating chamber is automatically snifted.

In the accompanying drawings and in the following specification I have shown and described my invention as applied to a preferred form of apparatus. It is to be understood, however, that the specific disclosure is for the purpose of exemplification only and that the scope of the invention is set out in the following claims in which I have endeavored to distinguish the invention from the prior art so far as known to me without, however, relinquishing or abandoning any portion or feature thereof.

In the accompanying drawings, Figure 1 is a side elevation of a well known form of carbonator with my invention applied thereto; Fig. 2 is a vertical section on an enlarged scale of certain of the more important features of the construction; Fig. 3 is a transverse section on the line 3-3 of Fig. 2; and Fig. 4 an elevation partly in section on line 4-4 of Fig. 1.

The same reference character is applied to each part wherever it occurs throughout the several views.

Referring first to Fig. 1, the ordinary form of carbonater shown comprises a reservoir 5 upon which is mounted a vertical saturating chamber 6 which communicates therewith in the usual manner. A pump 7 is connected by a pipe 8 with the top of the saturating chamber for supplying water thereto and said pump is driven in the usual manner and by mechanism which need not therefore be here described, from a power shaft 9 carrying a pulley 10. The belt shifter 11 normally holds the belt upon the idle pulley 12 being provided with a spring 13 for this purpose. But the rod 14 of the belt shifter is connected to a piston within a cylinder 15 which at times when the level of the water in the reservoir falls below the desired point forces the belt shifter to the right in said figure against the pressure of the spring to carry the belt onto the driving pulley. The piston in cylinder 15 is commonly operated by gas pressure led by a pipe 16 from the pressure regulator 17 to a valve cylinder 18 which is mounted on the end of the cylinder 15. Gas is supplied from any suitable source but preferably from the general supply of compressed car-

bonic acid by the pipe 17'. The valve 18 is operated when the liquid in the reservoir 5 falls below a predetermined point and for this purpose a tank 20 connected above and 5 below the normal water level with the reservoir 5 is suspended from a lever 21 and counterbalanced by a weight 22. A connecting rod 23 connects said lever with a bell crank 24 by which the valve 18 is operated, 10 see Fig. 4. Obviously when the water in the reservoir falls below a predetermined point the level in the suspended tank falls likewise so that the counterbalance weight overpowers the tank and shifting the lever 21 15 likewise shifts the lever 24 through the connection 23 and operates the valve 18 for admission of gas under pressure to the cylinder 15. The shifter thereupon shifts the belt to the driving pulley and the pump is 20 operated until such a level is reached that the equilibrium of the lever 21 carrying the tank is reestablished.

The above is a brief description of one of the most common forms of carbonating apparatus in use in connection with soda water fountains. My invention relates, as before observed, to an attachment for carbonators of this general description for drawing off or snifting the air from the 25 upper end of the saturating chamber at suitable intervals and automatically. For this purpose the snifting valve 25 is connected by a pipe 26 to the top of the saturating chamber 6 (see Fig. 1). A motor cylinder 30 35 27 for operating said valve is connected by a pipe 28 with the inlet chamber 29 of the motor cylinder 15 by which the belt shifter is operated so that when the gas under pressure enters the motor cylinder 15 it also enters the valve operating motor 27. The construction of the latter and also of the snifting valve is shown more particularly in Figs. 2, 3 and 4. The snifting valve comprises a casing 30 which may be conveniently mounted upon an attaching plate 31 and is formed in two sections connected by a screw thread 32.

The upper section 33 extends within the lower section and is formed at its lower 50 end with a wall 34 provided with a valve seat 35 extending into the lower section 36. The joint between the two sections is packed at 37 and the lower section is connected by a nipple 38 and socket to the pipe 26 referred to above. A reciprocating valve 39 normally engages the valve seat being held in contact therewith by a spring 40 inclosed by a sleeve 41 connected to the valve stem 42 and bearing against the upper surface of 55 the wall 34. The sleeve 41 slides within the upper section of the casing, and valve-stem 42 is enlarged to have a sliding fit within the valve seat 35 where it is provided with channels 42' for the passage of gas.

60 65 The motor for operating the valve com-

prises the casing 43 in which a piston 44 is free to slide. A piston rod 45 extends throughout the cap 46 of said cylinder, is slotted at its end outside the cylinder and provided with a transverse stud 47 which 70 loosely engages in an open slot 48 in the end of a link 49 pivoted at 50 to the valve stem. A stop 51 limits the movement of the piston to the right, as seen in Fig. 2. The connection between the piston rod and 75 valve stem is such as to permit lost motion so that the piston rod is free to finish its stroke in either direction but as the stud 47 passes over the valve it depresses the same through the link 49 so that the valve is 80 opened for a very short fraction of a second, permitting the escape of air and as the stud 47 passes on the valve is permitted to again return to its seat. Thus it is opened by the movement of the piston in each direction. 85 The pipe 28 heretofore mentioned is shown in Fig. 2 as communicating with the interior of the cylinder 43 at 52 and between the other end of the cylinder and the adjacent face of the piston a spring 53 is compressed which normally maintains the piston to the left. Thus the piston is given a complete reciprocation every time the pump is operated to supply water to the 90 saturator.

95 By suitably proportioning the parts the automatic snifting operation can be made to take care of the air carried into the saturating chamber, though if desired a hand snifting valve 54 may be added for use as required.

I claim:

1. In a device of the class described, a saturating chamber, a snifting valve connected therewith, a pump for supplying water to the device, means for throwing the pump into and out of operation and mechanism controlled by said means for operating the snifting valve.

2. In a device of the class described, a saturating chamber, a snifting valve connected therewith, a pump for supplying the device with water, means for throwing the pump into and out of operation comprising a fluid motor, means for operating the snifting valve comprising a fluid motor, and common means for admitting operating fluid to said motors.

3. In a device of the class described, a saturating chamber, a snifting valve connected therewith, a pump for supplying the device with water, means for throwing the pump into and out of operation comprising a fluid motor, means for operating the snifting valve comprising a fluid motor, and common means for admitting operating fluid to said motors controlled by the level of the water in the device.

4. In a carbonator a reservoir, a saturating chamber, a snifting valve connected to 130

- the saturating chamber, a pump for supplying liquid to the carbonator, means for throwing the pump into and out of operation comprising a fluid motor, means for operating the snifting valve comprising a fluid motor, the last said motor having a cylinder and piston, a link connection between the piston and snifting valve, a valve controlling the admission of fluid into said 5 motors, and means controlled by the level of the liquid in the reservoir for operating the last said valve.
5. In a carbonator, a reservoir and a saturating chamber, a pump and connections for 10 supplying water to the saturating chamber, a reciprocating snifting valve connected to the upper end of the saturating chamber, a fluid motor comprising a piston and rod, and lost motion connection between the rod 15 and valve whereby the latter is operated at each movement of the piston, means for 20 throwing the pump into and out of operation comprising a fluid motor and a valve controlled by the level of the water in the reservoir for admitting air into said motors. 25
6. In a carbonator a reservoir, a saturating chamber therein, a pump for supplying water to the carbonator, means for operating the pump, a device for starting and stopping the operation of the pump comprising a fluid operated motor, a snifting valve connected with the upper end of the saturating chamber, a fluid motor for operating the snifting valve arranged substantially perpendicular thereto, a loose link connection 30 between the valve and its motor, a connection between said motors, a valve controlling the admission of fluid to said motors, and means controlled by the level of the liquid in the reservoir for operating the last said 35 valve.

HORACE M. SMITH.
